UNITED STATES PATENT OFFICE.

PHINEAS B. MYERS, OF MORRISTOWN, NEW JERSEY.

PAPER BOX FOR CULTURE-TUBES AND SIMILAR ARTICLES.

1,021,998.

Specification of Letters Patent.

Patented Apr. 2, 1912.

Application filed January 30, 1912. Serial No. 674,277.

To all whom it may concern:

Be it known that I, PHINEAS B. MYERS, a citizen of the United States, residing at Morristown, county of Morris, and State of 5 New Jersey, have invented a new and Improved Paper Box for Culture-Tubes and Similar Articles, of which the following is a specification.

This invention relates to a paper box of 10 novel construction more particularly designed for holding culture tubes together with their swabs.

The box is composed of a minimum number of parts, may be readily folded and is 15 so constructed that it will maintain its charge securely in position and permit the same to be readily inserted and removed.

In the accompanying drawing: Figure 1 is a perspective view of a paper box embodying my invention; Fig. 2 a vertical transverse section thereof; Fig. 3 a plan of the box blank, and Fig. 4 a plan of the insert blank.

The box is of oblong form and provided 25 in proximity to one of its ends 10 with a vertical transverse partition 11 that divides off a pocket 12 adapted to contain the swabs 13 that are supported on the bottom 14 of the box. The larger compartment 15 30 formed between partition 11 and the other end 16 of the box is provided with a false bottom 17, a top plate 18 sunk below the upper edge of the box, and a partition 19 arranged between said top plate and the 35 false bottom 17. Top 18 and partition 19 are provided with a plurality of vertically aligned apertures adapted to accommodate the culture tubes 20. The lower ends of these tubes are supported upon the false 40 bottom 17 in such a way that the heads of the tubes are received within the space above top 18. Owing to the construction described, the swabs as well as the tubes extend upwardly to about the same level beneath the box cover 21, so as to be readily accessible though the length of the swabs exceeds the length of the tubes, such difference in length being compensated for by the elevation of false bottom 17 above box 45 bottom 14.

The box is composed of two blanks only, the first blank going to form the box proper together with partition 11, while the second blank goes to form an insert embodying the

false bottom 17 together with top 18 and 55 partition 19. The box blank proper is provided with the upright scored lines *a*, *b*, *c*, *d*, *e*, *f* and *g* that divide the blank into 8 upright strips 22; 11; 23; 10; 24; 16; 25 and 26. Strips 10, 24 and 16 extend above 60 and below the other strips and are by horizontally scored lines *h*, *i*, *j* and *k* divided into upper flaps 21, 27, 28, 29 and lower flaps 14, 30, 31 and 32. The blank is first folded on the upright lines in such a manner that partition 11 is placed into parallelism to box ends 10, 16 and secured by its gluing tab 22 to the box-back 24, while box front 25 is secured to end piece 10 by folded tab 26. The top and bottom of the 70 box are then formed by the upwardly and downwardly projecting flaps in the usual manner.

The insert blank is of oblong shape and provided with the scored lines *l*, *m*, *n*, *o*, *p*, 75 *q*, *r* and *s* dividing the same into a series of parallel strips 33, 34, 35, 18, 36, 17, 37, 19 and 38. Upon the scored lines the blank is so folded that the top 18, partition 19, false bottom 17 and a true bottom 34 are 80 brought into horizontal positions directly below one another, while strip 35 constitutes one of the sides, strips 36, 33 when overlapped and pasted together jointly constitute the other side, and strip 38 constitutes 85 the tab that is glued to the inner side of strip 36.

The insert constitutes a complete structure in itself which may be readily fitted into the main compartment 15 of the box 90 when the device is to be assembled and used. During transportation or storage, the box and insert remain separated and each may be folded into a flat form so as to occupy a minimum amount of space. 95

I claim:

A paper box comprising a foldable section that forms a box proper and an upright transverse partition integral therewith, and a removable foldable insert composed of an 100 apertured top plate, an apertured partition, a false bottom, a true bottom, and a pair of integral connecting sides.

PHINEAS B. MYERS.
